[57] CLAIM

The ornamental design for an eyeglass display fixture, as shown and described.

DESCRIPTION

FIG. 1 is a top, front and left side perspective view of the first embodiment of an eyeglass display fixture showing our new design, the broken line disclosure of an additional fixture, eyeglasses, and partial display panel being for illustrative purposes only and forming no part of the claimed design;

FIG. 2 is an enlarged front elevational view thereof;

FIG. 3 is an enlarged top plan view thereof;

FIG. 4 is an enlarged right side elevational view thereof;

FIG. 5 is an enlarged left side elevational view thereof;

FIG. 6 is an enlarged rear elevational view thereof;

FIG. 7 is an enlarged bottom plan view thereof;

FIG. 8 is a top, front, and left side perspective view of the second embodiment thereof, the only difference from the first residing in the length of the horizontal portion, and the broken line disclosure of an eyeglass and partial display panel being for illustrative purposes only and forming no part of the claimed design; and,

FIG. 9 is a top, rear, and right side perspective view of the second embodiment thereof, the broken line disclosure of a partial display panel being for illustrative purposes only and forming no part of the claimed design.
